5 Claims. (Cl. 179—18)

The present invention relates to automatic switching apparatus for use in automatic exchanges in which a plurality of communication channels is provided by means of a plurality of time interlaced pulse trains, and, in operation, when establishing communication between two stations connected to the exchange, apparatus associated with a first station selects a free one of the channels, a signal is transmitted to automatic switching apparatus associated with the second station identifying the selected free channel, and the said automatic switching apparatus serves to connect the second station to the identified free channel. Such automatic exchanges will be referred to hereinafter as "automatic exchanges of the kind specified" and examples of such exchanges are disclosed in co-pending United States patent applications Nos. 247,072, filed September 18, 1951, 257,786, filed November 23, 1951, and 257,991 and 257,992 filed November 24, 1951.

The object of the present invention is to provide suitable automatic switching apparatus for use in an automatic exchange of the kind specified to connect the said second station to the channel identified by the channel identifying signal.

According to the present invention automatic switching apparatus for use in an automatic exchange of the kind specified to connect the said second station to the channel identified by the channel identifying signal, comprises two or more gate devices, one of the gate devices being for transmitting messages from the first station to the second station, and the other gate device being for transmitting messages from the second station to the first station, selector means responsive to the channel identifying signal to select gating pulses in the selected free channel, and connections for applying the gating pulses to the said gate devices whereby communication between the two stations can be established in the selected channel through the two gate devices.

One arrangement in accordance with the invention will now be described by way of example with reference to the accompanying drawings in which

Figure 1 is a block schematic diagram of an automatic telephone exchange of the kind specified embodying automatic switching apparatus according to the present invention.

Figure 2 is a circuit diagram of one embodiment of the invention suitable for use in the automatic exchange of Figure 1, and

Figure 3 is a circuit diagram of a part shown in block form in Figure 2.

Figure 1 is a block schematic diagram of an automatic telephone exchange which is fully described in the specification of co-pending United States patent application No. 257,786. This exchange will not therefore be fully described in the present specification.

The telephone exchange shown in Figure 1 is suitable for use with 2000 subscribers. Of the 2000 subscribers stations connected to the exchange, one is shown at 10 and another at 11, the station 10 being terminated

2

in the exchange at "subscribers line circuit" 12 and the station 11 being terminated at the "subscribers line circuit 13."

The exchange comprises a group of 100 pulse communication channels the pulses in each channel having a recurrence frequency of about 8,000 P. P. S. This group of channels is provided by means including a pulse generator 14 adapted to generate pulses suitable for combination to provide the 100 channels time-interlaced at the pulse repetition frequency of 8,000 P. P. S. in each channel. The 100 channels are terminated by 100 "calling units" respectively of which one is shown at 15. 100 "called units" terminate the other ends of the channels respectively when in use, one of the "called units" being shown at 16. Messages between the calling and called units pass through a "GO speech junction" 17, a "return speech junction" 18 or a "metering and release junction" 19 as the case may be. In the event of a called subscriber being engaged a "busy signal" is transmitted to the calling subscriber by way of a "busy junction" 20.

For use in establishing calls between subscribers a number of alloters 24 and registers 23 are provided together with a signalling junction 25 and two further pulse generators 21 and 26.

Assuming the subscriber at the station 10 to be calling the subscriber at the station 11 the first operation occurs in the subscribers line circuit 12. This contains a finder which finds a free calling unit 15. An allotter 24 then comes into operation and allots a register 23 to the calling unit 15.

By means of the allotter and a finder in the register the calling unit found by the subscribers line circuit 12 is connected to the allotted register 23. A dialling tone is then automatically transmitted to the calling subscriber.

The output of the pulse generator 21 is in the form of a recurring sequence of 20 pulses which for convenience will be divided into groups of ten each. The first ten pulses in each sequence will be referred to collectively as the *d*' pulses and the second ten as the *u*' pulses. The ten *d*' pulses will be referred to individually as the pulses *d*'₀ to *d*'₉ respectively and appear at the terminals *Td'*₀ to *Td'*₉ respectively of the generator 21. The ten *u*' pulses will be referred to individually as pulses *u*'₀ to *u*'₉ and appear at the terminals *Tu'*₀ to *Tu'*₉ respectively of the generator 21.

Each of the calling units 15 is connected to one of the terminals *Td'*₀ to *Td'*₉ and to one of the terminals *Tu'*₀ to *Tu'*₉ of the generator 21, different ones of the calling units being connected to different pairs of the terminals *Td'* and *Tu'*. Thus each calling unit is identified by a different pair of *d*' and *u*' pulses and, as will be described later, the pair of *d*' and *u*' pulses identifying the calling unit, and hence the selected channel, is transmitted to the called subscriber's line circuit to identify the high grade channel on which communication is to be established.

When the calling subscriber hears the dialling tone and dials the number of the called subscriber, the dialling pulses are transmitted through the line circuit 12 and the seized calling unit 15 to the allotted register 23. In the register the four sets of dialling pulses are stored on four uniselectors. Four groups of ten pulses each, which will be referred to as the M, C, D and U pulses are applied to the four uniselectors in the register from the pulse generator 26. Thus the uniselectors in the register select one pulse from each of the four groups of recurring pulses applied thereto and it is arranged that these four selected pulses are combined to form a recurring output pulse which occurs in one recurring channel interval in a recurring sequence of 2,000

channel intervals. The sequence may recur for example at the rate of one per second and the 2,000 channels constitute a group of low grade signalling channels.

The recurring output pulse from the register is used as a gate pulse and permits the recurring pair of d' , u' pulses identified with the seized calling unit to pass to a signalling junction 25 only in the low grade channel interval determined by the gating pulse.

The output from the signalling junction is applied to all subscriber's line circuits. These circuits have gating pulses applied thereto however from the pulse generator 26, the gating pulses applied to each subscriber's line circuit being in the channel whose number corresponds to the subscriber's number on the exchange. Thus the only subscriber's line circuit to respond to a pair of d' , u' pulses appearing at the output of the signalling junction is that one whose gating pulse corresponds to the number dialled.

The called subscriber's line circuit then hunts for a free called unit and when a free called unit is found this unit functions to select appropriate pulses from the output of the generator 14 to enable the called subscriber to establish communication in the channel terminated by the seized calling unit. The called unit forms the subject of the present invention and one embodiment thereof will now be described in more detail with reference to Figures 2 and 3.

In Figure 2 a control terminal PI₂ is connected through relay contacts RB₃, a relay winding RQ and a battery BAT₂₈ to earth. The terminal PI₂ is connected to one fixed contact of a control bank of a uniselector forming part of the finder in the called subscriber's line circuit. The wiper of this bank is normally earthed. Two terminals +I₂ and -I₂ are connected through relay contacts F₂ and F₃ respectively and capacitors C₂₂ and C₂₃ to a winding MW₂ of a hybrid transformer HY₂. An output winding OW₂ of the transformer HY₂ has one terminal earthed and the other terminal thereof is connected through a capacitor C₂₄ to the control grid of a pentode valve V₂₄ whose cathode is earthed. The anode of the valve V₂₄ is connected through a load resistor R₃₂ to the positive terminal HT+11 of a source (not shown) of D. C. whose negative terminal is earthed. The anode is also connected through a capacitor C₂₅ to an output terminal RSP₂ which is connected to the "return speech junction" 18 of Figure 1. The screen grid is connected directly to the terminal HT+11. Negative bias is applied to the control grid of the valve V₂₄ from a bias terminal -GB₂₁. The suppressor grid is connected through a capacitor C₂₆ to relay contacts CD₁ and through a resistor R₃₃ to the negative terminal -GB₈ of a bias source (not shown).

An input terminal GSPO₁ which is connected to the output of the "GO speech junction" 17 of Figure 1 is connected through a capacitor C₂₇ to the control grid of a pentode valve V₂₅ whose cathode is earthed. The control grid of the pentode V₂₅ is also connected through a resistor R₃₄ to the negative terminal -GB₉ of a bias source (not shown) whose positive terminal is earthed. The anode of the pentode V₂₅ is connected through the primary winding of a transformer XF₂ to the positive terminal HT+12 of a source (not shown) of D. C. whose negative terminal is earthed. The anode is also connected through a capacitor C₂₈ to the control grid of a triode valve V₂₆ whose cathode is earthed. The anode of the triode V₂₆ is connected through a relay winding RB to the positive terminal HT+13 of a source (not shown) of D. C. whose negative terminal is earthed. The control grid of the triode V₂₆ is connected through a rectifier W₁₅ to the negative terminal -GB₁₁ of a bias source whose positive terminal is earthed. The screen grid of the pentode V₂₅ is connected through a resistor R₃₅ to the positive terminal HT+12. The suppressor grid is connected through a resistor R₃₆ to the negative terminal -GB₁₀ of a bias source (not shown) whose

positive terminal is earthed, and through a capacitor C₂₉ to the relay contacts CD₁.

The transformer XF₂ has two secondary windings S₁XF₂ and S₂XF₂. One terminal of the winding S₁XF₂ is connected to the negative terminal -GB₁₂ of a bias source (not shown) whose positive terminal is earthed, and the other terminal thereof is connected through a rectifier W₁₆ to the control grid of a pentode valve V₂₇ whose cathode is earthed. One terminal of the winding S₂XF₂ is connected to the negative terminal -GB₁₃ of a bias source (not shown) whose positive terminal is earthed, and the other terminal of the winding S₂XF₂ is connected through a rectifier W₁₇, and a resistor R₃₇ to the control grid of the pentode V₂₇.

A rectifier W₁₈ is connected between the terminal -GB₁₂ and the left-hand terminal of the winding S₂XF₂ in the drawing.

The primary winding of the transformer XF₂ is tuned by a capacitor C₃₀ which is shunted by a resistor R₁₉₄.

The anode of the pentode V₂₇ is connected through the input circuit of a low-pass filter FIL₂ to the positive terminal HT+14 of a source (not shown) of D. C. whose negative terminal is earthed. The screen grid of the pentode V₂₇ is connected through a resistor R₃₈ to the positive terminal HT+14 and is decoupled by a capacitor C₃₂. One output terminal of the low-pass filter FIL₂ is connected to earth and the other output terminal is connected through the winding IW₂ of the hybrid transformer HY₂ to earth.

The terminal -I₂ is normally connected to earth through the relay contacts F₃ and a battery BAT₃₃, and the terminal +I₂ is normally connected through the relay contacts F₂ and through one winding of a relay F to the moving contact of relay contacts RB₄. These contacts are normally open and the fixed contact thereof is connected through the secondary winding of a transformer XF₃ to earth. The primary winding of the transformer XF₃ is connected to terminals TR to which ringing current is applied from a suitable source (not shown). The contacts F₂ are bridged by a capacitor C₆₄. One terminal of the other winding of relay F is connected through a battery BAT₂₉ to earth and the other terminal thereof is connected through relay contacts F₁ and RB₁ to earth. One winding of a relay RD is connected between the right-hand plate (in the drawing) of the capacitor C₂₂ and earth. The other winding of the relay RD has one terminal connected to the right-hand plate of the capacitor C₂₃ and has the other terminal connected through a battery BAT₃₀ to earth.

A uniselector ZRU has three banks ZRU₁, ZRU₂ and ZRU₃, each of which has a home contact and bank contacts. The bank ZRU₁ has ten banks contacts which are connected to the translator 25 to be described later. The wiper of the bank ZRU₁ is connected through a resistor R₃₉ to the control grid of a gas-filled triode valve V₂₈. The cathode of the valve V₂₈ is connected to the negative terminal of a bias source GB₁₄ whose positive terminal is earthed. The anode of the valve V₂₈ is connected through relay contacts DA₁ to one terminal of a relay winding DA. The other terminal of the winding DA is connected through relay contacts RQ₁ and RB₂ in parallel to the positive terminal HT+15 of a source (not shown) of D. C. whose negative terminal is earthed.

The bank ZRU₂ is a homing bank and has its homing arc BC₆ connected to earth through relay contacts DA₂. The wiper of the bank ZRU₂ is connected through contacts ZRU_{dm}, operating winding ZRU, a relay winding CD and a battery BAT₃₁ in series to earth. The home contact of the bank ZRU₂ is connected through relay contacts RQ₂ to earth.

The bank ZRU₃ has ten bank contacts which are connected to ten terminals Tu₀ to Tu₉ respectively. The wiper of the bank ZRU₃ is connected through a resistor R₄₀ to the fixed contact of contacts CD₁.

A uniselector ZRD has three banks ZRD₁, ZRD₂ and

ZRD3, each of which has a home contact and bank contacts. The bank ZRD1 has ten bank contacts which are connected to the translator 25. The wiper of ZRD1 is connected through a resistor R₄₁ to the control grid of a gas-filled triode V₂₉ whose cathode is connected to earth through a bias source GB₁₅. The anode of the valve V₂₉ is connected through relay contacts UA1 to one terminal of a relay winding UA and the other terminal of the winding UA is connected through the relay contacts RQ1 and RB2 to the terminal HT+15.

The bank ZRD2 is a homing bank and the homing arc BC₇ is connected through relay contacts UA₂ to earth, and the home contact through RQ2 to earth. The wiper of the bank ZRD2 is connected through the mechanically operated contact ZFD_{dm}, the operating winding 15 ZRD, the relay winding CD and the battery BAT₃₁ in series to earth.

The bank ZRD3 has ten bank contacts which are connected to ten terminals Td₀ to Td₉ respectively. The wiper of the bank ZRD3 is connected through a rectifier 20 W₂₀ to the fixed contact of contacts CD1.

The moving contact of the contact CD1 in addition to being connected through the capacitors C₂₆ and C₂₉ to the suppressor grids of the pentodes V₂₄ and V₂₅ respectively is connected through a resistor R₄₂ to earth and 25 directly to the moving contact of contacts RD1. The fixed contact of contacts RD1 is connected through a resistor R₄₃ to earth and through a capacitor C₃₃ to the control grid of a triode valve V₃₁ whose cathode is earthed. Negative bias is applied through a resistor R₄₄ to the control grid of the triode V₃₁ from the negative terminal —GB₁₆ of a bias source (not shown) whose positive terminal is earthed. The anode of the valve V₃₁ is connected through a capacitor C₃₄ to an output terminal ASP₁, and through a resistor R₄₅ to the positive terminal HT+16 of a source (not shown) of D. C. whose negative terminal is earthed. The terminal ASP₁ is connected to the metering and release junction of Figure 1.

The translator 25 is connected through relay contacts RQ3 to the positive terminal HT+17 of a source (not shown) of D. C. whose negative terminal is earthed. Ten terminals Tu₀ to Tu₉ and ten terminals Td₀ to Td₉ are connected to the translator, and a further terminal CS₂ is connected to the called subscriber's line circuit to receive the pairs of d' u' pulses passed by the called subscriber's line circuit.

Referring now to Figure 3, this is a theoretical circuit diagram of the translator 25. The translator comprises two groups of gas-filled triode valves each group containing ten valves. A first of the groups contains ten triodes V₃₂ to V₄₁ whose cathodes are connected to earth through resistors R₄₆ and R₅₅ respectively, and directly to the ten bank contacts respectively of the uniselector bank ZRU₁. The anodes of the triodes V₃₂ to V₄₁ are connected together and through the relay contacts RQ3 to the terminal HT+17. The terminals Tu₀ to Tu₉ are connected through ten rectifiers W₂₁ to W₃₀ ten resistors R₆₆ to R₇₅ and ten rectifiers W₁₀₀ to W₁₀₉ respectively in series to the control grids of the triodes V₃₂ to V₄₁. The terminal CS₂ is connected through ten resistors R₈₆ to R₉₅ to the junctions of the rectifiers and resistors connecting the terminals Tu₀ to Tu₉ respectively to the control grids of the triodes V₃₂ to V₄₁. The control grids of the triodes V₃₂ to V₄₁ are connected through capacitors C₁₀₃ to C₁₁₂ and resistors R₂₀₇ to R₂₁₆ respectively to earth.

The second group contains ten triodes V₄₂ to V₅₁ whose cathodes are earthed through resistors R₅₆ to R₆₅ respectively. The cathodes of these valves are also connected directly to the ten bank contacts respectively of the uniselector bank ZRD1. The anodes of the valves V₄₂ to V₅₁ are connected together and through the relay contacts RQ3 to the terminal HT+17. The terminals Td₀ to Td₉ are connected through ten rectifiers W₃₁ 75

to W₄₀ ten resistors R₇₆ to R₈₅ and ten rectifiers W₁₁₀ to W₁₁₉ respectively in series to the control grids of the valves V₄₂ to V₅₁. The terminal CS₂ is connected through ten resistors R₉₆ to R₁₀₅ to the junctions of the rectifiers W₃₁ to W₄₀ and resistors R₇₆ to R₈₅ respectively.

In operation the d' and u' pulses arriving at the terminal CS₂ from the called subscriber's line circuit are applied to the control grids of the valves V₃₂ to V₅₁ through the resistors R₆₆ to R₁₀₅ and pulse lengthening 10 circuits comprising the rectifiers W₁₀₀ to W₁₁₉ and capacitors C₁₀₃ to C₁₂₂. The rectifiers W₂₁ to W₄₀ are, however, conducting to these pulses except the rectifiers to which d' and u' pulses are applied from the terminals Tu₀ to Td₉ simultaneously with the d' and u' pulses arriving at the terminal CS₂. In this example it will be assumed that the pulses d'₀ and u'₁ appear at the terminal CS₂ simultaneously with the pulses d'₀ and u'₁ applied at the terminals Td₀ and Tu₁. Thus the rectifiers W₃₁ and W₂₂ are non-conducting in this example and permit the d'₀ and u'₁ pulses applied to the terminal CS₂ to pass to the control grids of the valves V₄₂ and V₃₃ respectively. These two valves strike and hence their cathodes become positive.

When the wiper of the bank ZRU₁ reaches the bank contact connected to the cathode of the valve V₃₃ the positive potential appears at the control grid of the valve V₂₈ (Figure 2) and this valve strikes. Similarly the valve V₂₉ (Figure 2) strikes when the wiper of the bank ZRD1 reaches the bank contact connected to the cathode of the valve V₄₂.

Referring to Figure 2, when the valves V₂₈ and V₂₉ strike the relays DA and UA become energised by the anode circuits of these two valves. Thus the contacts DA₁, DA₂, UA₁ and UA₂ are operated. The contacts DA₁ hold the relay DA and extinguish the valve V₂₈ and the contacts DA₂ break the automatic stepping circuit of the uniselector ZRU. The contacts UA₁ hold the relay UA and extinguish the valve V₂₉, and the contacts UA₂ break the automatic stepping circuit of the uniselector ZRD.

Thus the wipers of the banks ZRD3 and ZRU₃ are arrested on the bank contacts connected to the terminals Td₀ and Tu₁ respectively. The pulses d₀ and u₁ are applied to these terminals respectively from the high frequency pulse generator. In the absence of a d₀ pulse the rectifier W₂₀ is conducting and hence the u₁ pulses are dropped across the resistor R₄₀. The occurrence of a d₀ pulse renders the rectifier W₂₀ non-conducting and hence the u₁ pulse occurring during each d₀ pulse passes to the contacts CD1 that is to say pulses in channel No. 1. These contacts close simultaneously with the opening of the automatic stepping circuit of the selectors and the pulses in channel No. 1 pass to the suppressor grids of the valves V₂₄ and V₂₅.

Thus unmodulated pulses of anode current flow in the valves V₂₄ and V₂₅ which are arranged to be normally non-conducting by the bias applied thereto from the terminals —GB₈ and —GB₁₀ respectively. The pulses passed by the valve V₂₅ are applied through the capacitor C₂₈ to the control grid of the valve V₂₆. Thus, pulses of anode current flow in this valve which is arranged to be normally non-conducting by the bias applied thereto from the terminal —GB₁₁. Thus the relay RB becomes energised and the contacts RB₁ and RB₄ thereof are operated.

The contacts RB₃ put an earth on the terminal PI₂. The contacts RB₂ close and hold the relays DA and UA when the relay RQ becomes de-energised on the operation of the contacts RB₃.

The contacts RB₄ close and apply ringing voltage from the transformer XF₃ to the called subscriber's station via the terminals +I₂ and —I₂. When the called subscriber answers the relay F becomes energised, the energising circuit being from earth through the battery BAT₃₃ the contacts F₃, the called subscriber's line, the

contacts F2, the relay winding F, the contacts RB4 and the secondary winding of the transformer XF3 back to earth. The contacts RB1 and F1 hold the relay F.

The relay RD then becomes energised, the energising circuit being from earth through the battery BAT₃₀, one winding of the relay RD, the contacts F3, the called subscriber's line the contacts F2 and the other winding of the relay RD back to earth.

The contacts RD1 then apply the pulses in channel No. 1 through the valve V₃₁ to the terminal ASP₁ and thence through the metering and release junction (19. Fig. 1) to the calling unit 15.

All pulses from the terminal GSPO₁ are passed to the control grid of the pentode V₂₅ which is gated by channel No. 1 pulses as previously described. Thus only the pulses in channel No. 1 pass to the transformer XF₂.

The primary winding is tuned by the capacitor C₃₀ to a periodicity of approximately twice the width of the pulses applied thereto from the valve V₂₅, and is heavily damped by the resistor R₁₉₄. The winding S₂XF₂ has more turns than the winding S₂XF₁ and hence provides a greater output voltage than S₂XF₁.

The terminal —GB₁₃ is arranged to be about five volts less negative than the terminal —GB₁₂.

Assuming the charge in the capacitor C₃₁ to be such that the potential of the upper plate thereof in the drawing is between that of —GB₁₃ and —GB₁₂, the rectifiers W₁₆ to W₁₈ are non-conducting. When a pulse arrives at the primary winding of the transformer XF₂ from the valve V₂₅ the leading edge of the pulse shock excites the transformer. The first, and negative, half-cycle of the free oscillation is applied to the anode of W₁₆ which, therefore, remains non-conducting, and to the cathode of W₁₇ which becomes conducting and hence C₃₁ discharges through R₃₇ and W₁₇ until the potential of its upper plate in the drawing equals the potential of the terminal —GB₁₂. Any further negative excursion at the cathode of W₁₇ is damped by W₁₈. Simultaneously W₁₉ becomes conducting and as a result the capacitor C₃₁ discharges further and its upper plate is left at a potential somewhat below that of the terminal —GB₁₂.

Just as this negative half-cycle ends, the lagging edge of the pulse arrives and again the transformer XF₂ is shock-excited but this time in the opposite sense. The first, and positive, half-cycle of this second free oscillation has no effect on W₁₇ and W₁₈. The capacitor C₃₁ is charged, however, through W₁₆ to a value dependent upon the amplitude of the pulse applied to the transformer XF₂, and lying between the potentials of the terminals —GB₁₂ and —GB₁₃.

The damping provided by the resistor R₁₉₄ is arranged to be sufficient to prevent subsequent half-cycles from affecting the charge in the capacitor C₃₁.

Thus the capacitor C₃₁ presents relatively broad pulses to the valve V₂₇ in response to relatively narrow pulses passed by the valve V₂₅, the amplitude of the broad pulses being dependent upon the amplitude of the narrow pulses.

The broad amplitude-modulated pulses are demodulated by being passed through the low-pass filter FIL₂ and the speech voltages are passed through the transformer HY₂, the capacitors C₂₂ and C₂₃, the contacts F2 and F3, and the called subscriber's line circuit to the called subscriber's line.

Speech voltages from the called subscriber are passed through his line circuit, and the hybrid transformer HY₂ to the control grid of the pentode valve V₂₄. Here they serve to amplitude-modulate the pulses (in channel No. 1) applied from the anode of V₂₄ to the terminal RSP₂. These pulses are applied through the Return speech junction to the calling unit.

When a call is ended and the calling subscriber replaces his handset on its rest it is arranged that the calling unit is released and hence pulses arriving at the terminal GSPO₁ of Figure 2 cease and the relay RB becomes de-

energised. The contacts RB1 reopen and release the relay F. The contacts RB2 open and release the relays DA and UA. Thus the contacts DA2 and UA2 close and the uniselectors ZRU and ZRD home. The called unit is then ready for use in making another call.

Although an arrangement has been described in which two pulses (d', u') are transmitted to the called unit in other systems a different number of pulses may be transmitted. For example where more than 100 channels are provided it will be necessary to transmit three pulses, one of which is representative of the 100's, the second of the 10's and the third of the units in the selected channel number. A further group of ten tubes is then added in Figure 3 and appropriate gating pulses applied thereto. 15 Likewise a further unisector is added in Figure 2 and controlled by the tubes in the third group in Figure 3.

We claim:

1. In combination, a selector device having a plurality of input terminals, an output terminal and selector means for selectively connecting the input terminals to said output terminal, means to apply pulse trains of different phases to said input terminals respectively, a control circuit to actuate said selector means, a source of control voltage connected to said control circuit to cause said selector means to select one of said input terminals for connection to said output terminal, a pulse demodulator, a pulse modulator and means to connect said output terminal to said demodulator and modulator.

2. In combination, a selector device having a plurality of input terminals, an output terminal and selector means for selectively connecting the input terminals to said output terminal, means to apply pulse trains having different channel identifying signals to said input terminals respectively, a control circuit to actuate said selector means, a source of control voltage connected to said control circuit to cause said selector means to select one of said input terminals for connection to said output terminal, a pulse demodulator, a pulse modulator and means to connect said output terminal to said demodulator and modulator.

3. A combination as set forth in claim 2 wherein each channel identifying signal includes a pulse whose instant of occurrence identifies a different pulse train, and wherein the selector means comprises a group of gas filled electron discharge tubes each of which has an anode, a cathode and a control electrode, a plurality of gate devices in the control electrode circuits of the several discharge tubes respectively, means for causing said gate devices to open in turn, and circuit means for applying a selected one of said channel identifying signals to the control electrodes of all said discharge tubes through said gate devices whereby the pulse of the said selected channel identifying signal passes to the control electrode of only one of said discharge tubes to strike said tube and identify a selected pulse train.

4. In combination, a selector device having a plurality of input terminals, an output terminal and selector means for selectively connecting the input terminals to said output terminal, means to apply pulse trains of different phases to said input terminals respectively, a control circuit to actuate said selector means, a source of control signals connected to said control circuit to cause said selector means to select one of said input terminals for connection to said output terminal, a pulse demodulator, a pulse modulator, and means to connect said output terminal to said demodulator and modulator.

5. A combination as set forth in claim 4, wherein each control signal includes a pulse, the instants of occurrence of pulses in different ones of said control signals identifying different ones of said pulse trains, and wherein the selector means comprises a group of gas-filled electron discharge tubes each having an anode, a cathode, and a control electrode, a plurality of gate devices in the control electrode circuits of the discharge tubes respectively, means for causing said gate devices to open in turn, and circuit means for applying a selected one of said control

signals to all said gate devices whereby the pulse of the selected control signal passes to the control electrode of only one of said discharge tubes to strike said tube and identify one of the said pulse trains to be selected.
